1 Claim. (Cl. 343—705)

The present invention relates to microwave aerials. Such aerials are generally excited at one of their ends by a primary source, for example, a horn.

This arrangement, which is generally satisfactory, requires the primary source to be matched to the radiating body. This matching may be difficult to achieve if the radiating body is very thin, for example, if it is a dielectric body along the surface of which surface waves propagate. As is known, in this case, the directivity is the greater, as the transversal dimension of the dielectric body is smaller. It is then extremely difficult to match a very thin piece to a horn.

It is an object of the invention to provide an aerial which avoids this difficulty.

The invention provides an aerial comprising a first radiating line which is energized by a second line extending parallel thereto and directly connected to the ultrahigh frequency energy source, this second line being in coupled relationship with said first line. The two lines are dimensioned in such a manner that, when there is no coupling, their phase propagation velocities are identical and their length is such that all the energy fed to the second line by the source is absorbed by the first line, on account of the coupling between these two lines.

The invention will be best understood from the following description and appended drawing, wherein:

FIG. 1 is an explanatory diagram of the principle of the invention;

FIG. 2 shows graphically the field distribution along the two transmission lines illustrated in FIG. 1 when they are coupled to each other;

FIG. 3 shows an embodiment of a transmission line which may be used for providing a distributed excitation;

FIG. 4 is a cross-sectional view of the line shown in FIG. 3;

FIG. 5 is a perspective view of a dielectric plate aerial; and

FIG. 6 shows an aerial according to the invention, comprising the lines illustrated in FIGS. 3 and 5.

In FIG. 1, two transmission lines 1 and 2 are shown along which the energy propagation is along parallel directions. Line 1 is excited by a source 3 and is terminated in a matched load 4. Line 2 terminates at its two ends in respective matched loads 5 and 7. The lines are such that, if, in the absence of any coupling therebetween, travelling waves propagate along them, they propagate with the same phase velocity.

If z is the abscissa of two points M_1 and M_2 located in the same plane, perpendicular to the respective axes of lines 1 and 2, x and y being the two other coordinates in this plane, the waves propagating along these lines may be expressed by the following relations:

$$A_1 = f_1(x, y) \cdot e^{-i\gamma_1 z}$$

and

$$A_2 = f_2(x, y) \cdot e^{-i\gamma_2 z}$$

γ_1 and γ_2 being the propagation coefficients or constants; as is well known by "propagation coefficient or constant," is meant a transmission characteristic of a line or medium,

2

which indicates the effect of the line on the wave being transmitted along the line;

$$\gamma_1 = \beta_1 + i\alpha_1$$

where

$$\gamma_2 = \beta_2 + i\cdot\alpha_2$$

with

$$\beta_1 = \beta_2$$

If lines 1 and 2 are coupled to each other, c being the coupling coefficient, it may be shown that the field in line 1 results from two travelling waves, namely wave A_1 and another wave A_{31} , the propagation constant of which is:

$$\gamma_{31} = \gamma_1 - 2c \quad (1)$$

Similarly, in line 2, wave A_{32} has a propagation constant $\gamma_{32} = \gamma_2 + 2c$. By "coupling coefficient" or "coefficient of coupling" is meant "a numeral rating between 0 and 1, that specifies the degree of coupling between the two circuits."

Waves A_{31} and A_1 being in phase with wave A_1 , the field in line 1 may be expressed by the following relation:

$$B_1 = 2f_1(x, y) \cdot \cos cz \cdot e^{-i(\gamma_1 + c)z} \quad (2)$$

In line 2, wave A_{32} is in phase opposition with A_2 and the field is then:

$$B_2 = 2f_2(x, y) \cdot i \sin cz \cdot e^{-i(\gamma_2 + c)z} \quad (3)$$

This is true even if α_1 differs from α_2 ; it is also true when one of the lines, for instance line 2, is dissipative, on account of ohmic losses or radiation.

In FIG. 2, there is shown, for a low radiation, the distribution of amplitudes B_1 and B_2 along the axes of propagation of the two lines O_1z_1 and O_2z_2 . Between O and a point of abscissa l , line 1 gives up energy to line 2, the field amplitude decreasing with z in line 1 and increasing in line 2.

Formulae 2 and 3 show that amplitudes B_1 and B_2 vary periodically with z , the period being π/c . For $z=l$, with

$$l = \frac{\pi}{2c} \quad (4)$$

the whole of the energy is transferred from line 1 to line 2.

If the respective lengths of lines 1 and 2 are made equal to l , no energy is dissipated in load 4, the whole of the energy in line 1 being transferred to line 2. This energy is either radiated by line 2 or absorbed by loads 5 and 6.

Thus, by conveniently selecting the length of lines 1 and 2, line 2 may absorb and radiate all the energy of line 1.

The invention thus provides a novel method for exciting radiating lines.

An aerial of particular interest, incorporating the above principles, will now be described, by way of example, in more detail.

FIG. 3 shows a flat-shaped line which does not radiate much energy and which may be used as line 1. It comprises a thin metal plate or strip 10, having a width a , which is separated from two practically infinite conductive plates 20 and 30 by gaps having a width b . The line is excited by a coaxial line 5, whose inner conductor 4 is coupled to plate 10, while plates 20 and 30 are connected to its outer conductor. Line 5 is excited by a source 6. In the embodiment shown in FIG. 3, the line assembly is supported on a dielectric plane support.

In FIG. 4, the same line is shown in cross-section. The lines of force of the electric field are in phase opposition in the two gaps. Consequently, the wave propa-

gating in the line is a TEM-wave, the phase velocity of which is equal to the velocity of the light, with

$$\beta_1 = \beta_0 = \frac{2\pi}{\lambda_0} \quad (5)$$

where λ_0 is the wave-length in the space.

The line has a very low attenuation coefficient α_1 , the ohmic losses and the radiation losses being negligible.

FIG. 5 is an embodiment of a transmission line which may be used as line 2 of FIG. 1. It comprises a dielectric plate or strip 7, of a thickness h , which is supported on a metal plate 8. Let Oz be the direction of propagation of a surface wave along the plate, Ox and Oy being the two directions perpendicular to Oz. If h is small with respect to the wavelength λ_0 , i.e. if

$$u = \beta_0 h = \frac{2\pi h}{\lambda_0} \quad (6)$$

is very small, it can be shown that only a TM-wave can propagate in the plate, this wave having a propagation constant β_2 which is substantially equal to β_0 :

$$\beta_2 = \beta_0 \left[1 + 1/2 \cdot \left(\frac{\epsilon - 1}{\epsilon} \right)^2 \cdot u^2 \right] \quad (7)$$

where ϵ is the dielectric constant of the strip.

It may be shown that such a line has a maximum radiation along the axis Oz.

Everything happens as though, along the line, all of the energy of the wave were contained in an air layer of a thickness L and the radiation is of the "end-fire" type. The directivity is all the greater, as L is greater. If $\Delta\theta$ is the width of the radiating pattern 3 db below the maximum, it may be shown that:

$$v \cdot \sin \frac{\Delta\theta}{2} = 1 \quad (8)$$

with

$$v = \beta_0 L = \frac{\epsilon - 1}{\epsilon - 1} u \quad (9)$$

The aerial gain is substantially

$$G = 2v \quad (10)$$

All these results are well known in the art. But, up to the present, it was not known to excite aerials of a reduced thickness h by means of horns located at one end of the line. As a matter of fact, the characteristic impedance of such a plate is the higher, as h is smaller. It is therefore difficult to match a waveguide to such a line. The present invention makes it possible to achieve this result.

FIG. 6 illustrates an assembly comprising lines 1 and 2. Line 2 comprises two conductive plates 81 and 82, having a width large enough to be considered infinite for all practical purposes. These plates respectively support dielectric plates 72. Plates 81 and 82 also serve as conductive plates 20 and 30 of FIG. 3, conductor 83 corresponding to conductor 10 of the same figure. The assembly 81-82-83 thus builds up line 1 of FIG. 1. The whole assembly has the length l defined by Formula 4.

The coupling coefficient c depends on the width h and the distance d between the gaps and the edge of the dielectric plates 72. This distance d must be small, since the coupling decreases very rapidly as d increases.

Equation

$$v = \sin \frac{\Delta\theta}{2} = 1$$

defines the thickness h of the dielectric since

$$h = \frac{\epsilon - 1}{\epsilon - 1} u$$

and $h = u/\beta_0$.

This thickness is sufficiently small relative to the wavelength for the phase velocity of the surface wave propa-

gating along line 2 to be equal to the velocity of light in free space.

In one embodiment of the invention, one had $\lambda_0 = 10$ cm. and $h = 0.4$ cm.

The dielectric selected had a small loss angle ("silirite") and $\epsilon = 4$.

Under these conditions, one had

$$\beta_1 = \beta_0 \left[1 + \frac{1}{2} \cdot \frac{(\epsilon - 1)^2}{\epsilon^2} \cdot u^2 \right]$$

and $\beta_1 - \beta_0 = 1.6 \cdot 10^{-2}$:

$$u = 0.24$$

$$v = 5$$

therefore

$$\frac{\Delta\theta}{2} = 20^\circ$$

The gain G is equal to 32, or 15.2 db with respect to a half-wave dipole.

The above Formulae 6 and 9 show that parameters u and v , which define the radiating pattern of the aerial and the maximum gain, vary as a function of the first power of the frequency of the transmitted wave.

In addition, no device showing a significant Q-factor is made a part of the aerial. Therefore, the aerial can have a wide frequency range, which may attain and even exceed the octave, as confirmed by the experience. The experience has shown indeed that, for a frequency range extending from 2000 to 4000 megacycles, i.e. for an average wave-length λ_0 of 10 cm., the radiating pattern actually presents the characteristics according to Formulae 8, 9 and 10.

In this range, the width of the radiation beam at 3 db below the maximum is close to 20° according to Formula 8.

The maximum gain has been experimentally found to be comprised between 16 and 20 db, which is quite consonant with the theoretical results of Formula 10.

The aerial has a highly flat structure and can be readily applied onto the surface of an aircraft or other flying body without affecting the aerodynamic qualities thereof.

What is claimed is:

A device for radiating ultra high frequency energy comprising: a first and a second transmission line parallel to each other; said first line comprising a first conductive strip, having a thickness small relatively to the operating wavelength, extending in a predetermined direction, and having two parallel sides, two infinite and conductive first planes, respectively extending along said sides and separated therefrom by respective gaps, means for coupling an ultra high frequency source to said line for creating electromagnetic fields in said gaps; said second transmission line comprising two second strips of a dielectric material, respectively supported on said first planes, at the same distance from said gaps, said first strip and said second strips having the same length equal to $\pi/2c$, c being the coupling coefficient between said two lines.
